UNITED STATES PATENT OFFICE.

WALTER M. AUSTIN, OF SWISSVALE, PENNSYLVANIA, ASSIGNEE TO WESTINGHOUSE ELECTRIC AND MANUFACTURING COMPANY, A CORPORATION OF PENNSYLVANIA.

METHOD OF MAKING TRIPPING COILS.

Application filed September 27, 1922. Serial No. 590,770.

This invention relates to circuit breakers and more particularly to tripping coils therefor and to methods of making the same.

The object of my invention is to provide 5 a metallic coil which may be integrally cast by a single operation.

Another object of my invention is to provide a metallic coil of such shape that a single simple core member is sufficient for 10 the casting thereof.

A further object of my invention is to materially reduce the amount of labor heretofore required in the manufacture of metallic coils.

15 Metallic coils have heretofore been constructed by bending strips of metal through the required number of convolutions. Sometimes this could be done by a "cold" process but more frequently a heat treatment, in 20 addition to the mechanical operation, was required to effect the desired result. Such processes are complicated and expensive.

By my invention, I provide a coil so designed that it may be cast by a single 25 operation, requiring but a simple mold pattern.

Figure 1 illustrates a conventional carbon-and-air circuit breaker equipped with a tripping coil embodying my invention.

30 Figure 2 is an edge view of the coil as it appears upon removing from the mold.

Figure 3 is a sectional view of the same, taken along the line III—III of Figure 2.

Figure 4 is an end view of the same.

35 Figure 5 is a side view of the completed coil, and

Figure 6 is an edge view of the same.

In Figure 1, is shown a conventional carbon-and-air circuit breaker 1, mounted on a 40 base 2 and equipped with a tripping coil 3 embodying my invention. It is to be understood that the use of this coil is not confined to carbon-and-air circuit breakers, but that it may have other applications.

45 The coil 3 may comprise any desired number of convolutions 4 and end members 5 and 6 extending parallel to the major axis of the coil 1. The convolutions 6 are substantially alike in cross-sectional area, each 50 has different cross-sectional areas in different portions thereof, as indicated in Figure 4.

By a comparison of Figures 2 and 4, it may be seen that the radial thickness of each 55 convolution 4 is less at its outer side than

at its inner side; while the longitudinal thickness of each convolution is greater at the outer side than at its inner side.

Because of this disposition of material, it is possible to secure the effect of an additional turn at the inner side of the coil without increasing the over-all dimensions. This feature is clearly shown in Figure 6 where four convolutions at the inner side, 60 occupy the endwise space of three convolutions at the outer side.

By reference to Figure 4, it may be seen that the coil, when removed from the mold, is not truly helical but that the sides are slightly flattened. As is shown in Fig. 3, 70 the outer and inner portions of each convolution are nearly flat, while the intermediate portions are abruptly curved.

Each convolution is provided with a shoulder 7 and a recess 8, shoulders 7 being 75 adapted to fit into the recesses 8 of the adjacent convolutions. By reason of the peculiar design of the shoulder 7 and recess 8, it is possible to mold the coil 3 in a single operation and with a single cylindrical core 80 member.

The disposition of the shoulders 7 and recesses 8 is such that there is nothing to interfere with drawing the pattern from the sand. By a comparison of Figs. 2 and 3, 85 it may be observed that there is practically a uniform distance between corresponding points on the several convolutions throughout their length. This feature is of great importance from a practical standpoint, as 90 it makes possible the use of a green-sand mold and a cylindrical dry sand core in the casting of the coil.

After the coil 3 has been removed from the mold, it is cleaned and placed under pressure 95 in a direction parallel with the axis thereof. The effect of this pressure is to force the convolutions toward each other so that they occupy the relative positions shown in Figures 5 and 6. The coils are then machined and drilled for openings 9, 11 and 12. These openings are for attaching screws and binding posts, one of which is shown, as at 13, in Figure 6. The pressing process also serves to flatten out the abrupt curves in each convolution and thereby increases the length 100 of the radii of curvature.

Suitable air spaces 14 are left between the 110 several adjacent convolutions 4 for the purpose of insulating them from one another.

It is thus seen that I have provided a metallic coil which may be made in a single casting operation with the use of a green-sand mold and the simplest core. The cross-sectional shapes of the convolution 4 are varied at points throughout their length in order that all available space may be used to the best advantage.

My invention is not limited to the forms that are illustrated or to the arrangement thereof, since modifications may be made therein within the spirit and scope of the invention, as set forth in the appended claims.

I claim as my invention:

- 15 1. A method of making a helical element which consists in casting the helix with spaces between the various convolutions and then subjecting the helix to pressure, whereby the convolutions are brought nearer together.
- 20 2. The method of making a helical member which consists in casting a true helix and then submitting the helix to mechanical pressure.
- 25 3. The method of making a helical member which consists in casting an extended helix and then submitting the helix to mechanical pressure applied in the direction of the axis of the helix.
- 30 4. The method of making a helical element which consists in casting a helix, with the

convolutions in an extended position, and then subjecting the helix to pressure in the direction of its axis, whereby the convolutions are brought close together.

5 5. The method of making a helical element which consists in casting a helix with the various convolutions in such extended relation that sand may be used as a molding element between said convolutions, then removing 40 said helix from the mold and subjecting the same to pressure, whereby the various convolutions are brought nearer together.

6. The method of making a helical element which consists in casting the same in a green- 45 sand mold.

7. The method of making a helical element which consists in casting said element, with the various convolutions spaced apart, and with portions of said convolutions having 50 plane surfaces with abruptly curved surfaces between said plane surfaces, then compressing said helical element in a direction whereby said convolutions are brought together and the length of the radii of curvature of 55 the curved surfaces are materially increased.

In testimony whereof, I have hereunto subscribed my name this 20th day of September, 1922.

WALTER M. AUSTIN.
